COMBINED CLIP DISPENSER AND PENCIL HOLDER

Robert M. Leedy, 7 Martindale Road,
Short Hills, N.J. 07078

Filed Dec. 4, 1972, Ser. No. 311,651

Term of patent 14 years

Int. Cl. D19—02

U.S. Cl. D74—5 A

FIG. 1

FIG. 2

FIG. 3

FIG. 4

FIG. 1 is a perspective view of a combined clip dispenser and pencil holder showing my new design;

FIG. 2 is a front elevational view thereof;

FIG. 3 is a top plan view; and

FIG. 4 is a bottom plan view.

The undisclosed sides of the combined clip dispenser and pencil holder are plain and unornamented.

I claim:

The ornamental design for a combined clip dispenser and pencil holder, as shown and described.
